UNITED STATES PATENT OFFICE.

HARVEY J. FLINT, OF EDGEWOOD, RHODE ISLAND.

DESIGN FOR A BROOCH.

No. 40,101.

Specification for Design.

Patented June 29, 1909.

Application filed May 3, 1909. Serial No. 493,753. Term of patent 3½ years.

To all whom it may concern:

Be it known that I, HARVEY J. FLINT, a citizen of the United States, residing at Edgewood, in the town of Cranston, county of Providence, and State of Rhode Island, have invented a new, original, and ornamental Design for Brooches, of which the following is a specification, reference being had to the accompanying drawings, forming part thereof.

Figure 1 is a top plan view showing the ornamentation of the brooch. Fig. 2—is a perspective view looking at the top and side of the brooch, and also illustrating the thickness of the plate and the apertures therethrough. Fig. 3—is a perspective view looking at the under side of the brooch.

The design of the brooch consists essentially of a bar divided into squares, each square being surrounded with a narrow border line. The first, last, and every alternate square is filled in with enamel, on the face of which enamel appears a line design. The second and every alternate square is hollow and in these hollow squares is set or supported an ornamental gem.

I claim:—

The ornamental design for a brooch as shown and described.

HARVEY J. FLINT.
